ATTORNEY

UNITED STATES PATENT OFFICE.

CHARLES F. COOKE, OF CHICAGO, ILLINOIS.

DESIGN FOR A HIGHWAY SIGN.

61,086.

Specification for Design. Patented June 20, 1922.

Application filed October 13, 1921. Serial No. 507,545. Term of patent 14 years.

To all whom it may concern:

Be it known that I, CHARLES F. COOKE, a citizen of the United States, residing at Chicago, in the county of Cook and State of Illinois, have invented a new, original, and ornamental Design for a Highway Sign, of which the following is a specification, reference being had to the accompanying drawing, forming part hereof.

The figure is a plan view of a highway sign, showing my new design.

I claim:

The ornamental design for a highway sign, as shown.

CHARLES F. COOKE.
